N° 1,017

Design for "Prairie Flower"
Cooking Stove

By
Joseph A. Reed
Assignor to Stuart & Peterson

Patented June 29, 1858.

Dec. 1017

Joseph A. Read, of Philadelphia, Pa,
Assignor to
David Stuart & Richard Peterson, of same place,
Letters Patent No. 1017, dated June 29, 1858.

The schedule referred to in the Letters Patent, and making part of the same.

To all whom it may concern:

Be it known that I, Joseph A. Read, of the City of Philadelphia and State of Pennsylvania, have invented or produced a new or original design for plates of a cooking stove termed the "Prairie Flower", and I do hereby declare the following to be a full and exact description of the same, reference being had to the accompanying drawing, which forms a part of this specification, and in which,

Fig. 1. represents a view of the side plate resting on the bottom plate,

Fig. 2. a view of the front plate,

Fig. 3. a view of the end plate,

Fig. 4. a plan view of the bottom plate, and

Fig. 5. a sectional view (full size) of the moulding of the bottom plate.

The side plates are edged with plain mouldings a. a. a. on the top and two ends, and on the bottom with an undulating or waved moulding b. An oven door A. and fire door B. are hinged to the side plates, each door being edged partially with straight mouldings c. partially with curved mouldings d. inside of the latter, with denticated mouldings e. Both doors have foliated ornaments in alto relievo. On the side plates is also a permanent panel C with a foliated ornament similar in character to that of the oven door, and surrounded with a waved and denticated moulding. Above

2

Des. 1017

the oven door is a foliated scroll D, with the name of the Stove in raised letters.

The front plate of the Stove is edged with a plain moulding, and has two doors E, and E', with partially plain and partially denticated mouldings on the edge, and with a foliated ornament of similar character to that of the panel C. Above the doors are a series of openings f, with ornaments between each. The end plate (Fig. 3,) has a rounded panel E', with a foliated ornament, corresponding to that on the oven door, (Fig. 1,) and on each side of this panel, a plain panel G, edged with plain and denticated mouldings. The bottom of the straight portion of the plate has a waved moulding, similar to that on the bottom of the side plate. The bottom plate, (Fig. 4,) has, round its edges, a moulding of the form represented in the section, Fig. 5, with projecting ornaments, similar to those illustrated at x.

I claim and desire to secure by Letters Patent:

The combination and arrangement of the ornamental figures and forms, represented in and by the accompanying drawing, as forming together an ornamental design for plates of a cooking stove.

In testimony whereof, I have signed my name to this Specification before two subscribing witnesses.

Exd.   Witnesses
J. M. S.   C. Brazer.
Henry Odiorne.
